RATION OF MISSOURI.

SEAM FOR SHOE-SOLES.

1,072,211.

Specification of Letters Patent. Patented Sept. 2, 1913.

Application filed September 1, 1911. Serial No. 647,263.

To all whom it may concern:

Be it known that we, GEORGE A. DOBYNE and STEPHEN A. DOBYNE, citizens of the United States, and residing at St. Louis, in 5 the State of Missouri, have invented certain new and useful Improvements in Seams for Shoe - Soles, of which the following is a specification.

This invention relates to shoes and more 10 particularly to a seam for fastening the outsole on the shoe.

In the manufacture of shoes, the sole is ordinarily attached by a stitched seam with a sewing machine. In a McKay shoe the 15 stitches pass through the outsole, upper and insole, and sometimes through a tap or slip sole which is placed between the outsole and upper. Various methods have been proposed 20 for making a metallic seam in a McKay shoe, but without success, since the seams heretofore used rendered the sole and the entire shoe stiff and not flexible like a sewed shoe. Therefore although a metallic seam 25 has superior wearing qualities, and requires for its production less complicated machinery and less skilled operators than a sewed seam, it has not been possible heretofore to provide an efficient metallic seam which will leave the sole flexible and at the same time 30 possess good wearing qualities.

One of the objects of this invention therefore is to provide a metallic seam for attaching the outsole of a shoe which will possess all the desirable characteristics and 35 qualities of both a sewed seam and a metallic seam, and which can be made with simple machinery and by unskilled operators.

When a metallic seam is used in McKay shoes, the fasteners of the seam are driven 40 through the outsole and insole and clenched back into the insole. This leaves the clenched points on the inside face of the insole, and as the outsole is worn down, causing the heads of the fasteners to wear off, the tendency 45 is to cause the clenched points to work up through the insole and thus leave objectionable projections on the inside face of the insole. Furthermore a loose anchorage of the clenched point will cause the fastener 50 to project a short distance beyond the outsole thereby marring polished floors.

Another object of this invention therefore is to provide a metallic seam for shoes in

which the clenched points of the fasteners are so anchored that these fasteners cannot 55 move in directions either toward the foot or toward the outsole.

The invention will be fully described in connection with the accompanying drawings 60 in which:

Figure 1 is a side elevation of a McKay shoe, parts being broken away to show the novel seam in section, Fig. 2 is a cross section of the shoe shown in Fig. 1, and Fig. 3 is a section along the seam, Fig. 4 is a cross 65 section through another form of shoe in which the channel is dispensed with, and Fig. 5 is a section along the seam, Fig. 6 is a detail of one of the fasteners and an enlarged view of its point, Fig. 7 is a view of 70 the fastener in string form, Fig. 8 is a section of the seam at the shank of the shoe shown in Fig. 1, Fig. 9 is a section of the seam illustrating its construction and operation, and Fig. 10 is an enlarged section of 75 the seam showing the construction of the clenched point.

Referring to the drawings, 8 designates the shoe, 10 the upper, 11 the insole, 12 the tap or slip sole, and 13 the outsole. The 80 fastener 14 is provided with a laterally extending well defined and non-clenching head 15 as distinguished from an inturned hook-shaped or clenched head, the head tapering inwardly to the shank of the fastener as 85 shown at 16.

The fastener is preferably of the string-nail type, a string T being shown in Fig. 7. The point 17 of the fastener is turned or deflected slightly to make an abrupt bend 90 as shown in Fig. 6. This is accomplished in the process of cutting the preceding fastener from the string as fully described in our copending application, Serial No. 647,264, filed of even date herewith. In 95 whatever manner this is accomplished, the object is to so form the point that the direction of the clench will be controlled, whereby the points will be clenched in a predetermined direction by the clenching anvil. 100 The points are preferably turned in the same direction as the heads 16 so that the points will be clenched in the same direction as the heads. The string is made by cutting pieces out of one edge of a strip. This will leave 105 the cut edge a of the fastener weaker than

the uncut edge *b*, which edge *b* has been rolled and strengthened in the operation of rolling the strip or wire. This will therefore also insure that the point will clench in the direction of its weaker edge *a* so that the point will always clench in a predetermined direction, making the uncut edge *b* the outer or convex edge of the clenched point.

10 In the construction of the seam the fasteners are inserted through the layers comprising the sole so that the heads will lie at the outer face of the outsole and so that these heads will extend in the direction of 15 the seam as shown in Figs. 3 and 5. Where a channel is used these heads lie in the channel 19 and are then covered by turning down the channel flap 20, but where no channel is used, the heads lie substantially 20 flush with the outer face of the outsole as shown in Figs. 4 and 5 or are slightly countersunk. The points 17 are clenched and turned back into the insole, and the construction of the point and the fastener itself 25 is such, as described above, and the clenching anvil is so constructed, that the points as clenched and turned back will extend in the same direction and in the direction of the seam. In the completed seam therefore 30 the heads as well as the points will extend in the same direction and in the direction of the seam. At the shank of the shoe where the sole is thinner than at the fore part, the points will be clenched more as shown 35 in Fig. 6, and it is therefore not necessary to use two sizes of fasteners for the fore part and shank respectively.

In referring to Fig. 10 it will be noted 40 that the point of the nail is clenched back into the insole. In the formation of the clench the deflected point will be turned toward the shank of the fastener. Moreover when the deflected point of the nail strikes the anvil it will itself be bent laterally so 45 that when it turns back into the insole it will curl toward the shank. This will give the clenched point the effect of fish hook anchorage, the laterally deflected point acting as a barb to prevent the clenched point 50 from working upwardly above the upper face of the insole. The nail is thus supported in the sole against movement either upwardly or downwardly. The nail will therefore wear uniformly with the sole and will 55 not project beyond the face of the outsole even if the nail head wears off. The beveled nail head does however assist materially to maintain the firm grip of the seam.

Referring now to Fig. 9, *a* represents the 60 outside face of the outsole and *i* the inside face of the insole. A shoe sole must be capable of being flexed inwardly and must therefore be flexible when bent in that direction. It need not however necessarily be 65 very flexible in the other direction, *i. e.*,

when flexed outwardly. In bending or flexing the united soles inwardly the fibers at the inside face *i* of the insole will be placed under compression, while the fibers at the outer face *a* of the outsole will be placed 70 under tension. Practically in a laminated structure like the combined insole, upper, tap sole and out-sole, the elongation of the outside fibers is greater than the compression of the inside fibers. In the complete 75 sole attached by our novel seam the fibers in the outsole are as free to elongate as if the fastener were not present, since neither the heads nor the shanks of the fasteners will restrain any such movement, as is the 80 case with staple fasteners and like prong fasteners which bind a part of the material between the legs of the fasteners and restrict free elongation. At the face of the insole are located the clenched points of the fasteners, but these points will not retard the 85 free movement of the fibers. As stated above the movement of the fibers at the insole is one of compression. Now since the points are all clenched in the same direction 90 and in the direction of the seam, the movement of the fibers over one another is not retarded by their presence, but these rounded clenched ends turn and roll in the leather and thus permit free inward flexing of the 95 sole. Since the heads and the clenched points extend in the same direction in the seam, one will not interfere with the other in restricting the movement of the fibers when the sole is flexed. It will thus be seen 100 that in view of the fact that the heads are located in the outsole and the clenched points in the insole, and in view of the fact that the clenched points as well as the heads extend in the direction of the seam, the resultant seam will be exceedingly flexible in 105 the required direction, *i. e.*, when flexed inwardly as is the case when the shoe is worn.

It will thus be seen that the invention accomplishes its objects. A seam is produced 110 which will be practically as flexible as a sewed seam, but will possess better wearing qualities, and this seam can be made in simple machines compared with the McKay sewing machine, and can be made by unskilled operators. The clenched points are turned back into the insole so that the inside face of the insole will be left perfectly smooth, since the projecting point itself is buried in the leather, leaving only a rounded part exposed on the face of the insole. The fish hook anchorage will moreover prevent the clenched points from working up 115 above the face of the insole. The sock sole usually required in McKay shoes may therefore be dispensed with. The fasteners may be countersunk in the outsole, and the holes can be closed in the leveling and scouring operations, so that the outsole will be left 120 smooth. The channel and its accompany- 125

ing channeling operation can therefore be omitted, thus resulting in a saving of cost of manufacture.

Having thus described the invention what is claimed is:

5 1. A shoe having an outsole and an insole, and a metallic fastener seam for attaching said outsole comprising fasteners passing through the outsole and insole and clenched back into the insole, the clenched points of said fasteners having their ends deflected toward the shanks thereof.

10 2. A shoe having an outsole and an insole, and a metallic fastener seam for attaching 15 said outsole comprising fasteners passing through the outsole and insole and clenched back into the insole in the same direction and in the direction of and along the seam, the clenched points of said fasteners having

their ends deflected toward the shanks 20 thereof.

3. A shoe having an insole and an outsole, and a metallic fastener seam for attaching said outsole comprising fasteners having well defined beveled non-clenching heads, 25 the fasteners extending through the outsole and insole, with the heads in the outsole and the points of said fasteners clenched back into the insole, the clenched points of said fasteners having their ends deflected toward 30 the shanks thereof.

In testimony whereof we affix our signatures in presence of two witnesses.
